UNITED STATES PATENT OFFICE.

CLARENCE L. BAIR, OF DETROIT, MICHIGAN, ASSIGNOR TO AUTO SPECIALTIES MANUFACTURING CO., OF ST. JOSEPH, MICHIGAN, A CORPORATION OF CALIFORNIA.

BOW-TOP HOLDER FOR TOPS WITH NON-DETACHABLE REAR CURTAINS.

1,306,162.

Specification of Letters Patent. Patented June 10, 1919.

Application filed May 29, 1916. Serial No. 100,499.

To all whom it may concern:

Be it known that I, CLARENCE L. BAIR, a citizen of the United States, residing at Detroit, in the county of Wayne and State 5 of Michigan, have invented a certain new and useful Improvement in Bow-Top Holders for Tops with Non-Detachable Rear Curtains, of which the following is a specification.

- 10 This invention relates to bow top holders for vehicles of the general type shown in my Patent Number 1,010,110, issued November 28th, 1911, designed to hold the supporting bows of a vehicle top in separated position one from the other when the top is collapsed. The object of this invention is to provide a holder of this class of such a construction that it can be used to confine the bows of a top which has a solid rear curtain 15 attached to the bottom bow of the vehicle, which class of top cannot be taken care of with the bow holders of types shown in my above mentioned patent. The invention consists in providing a bow holder which, while 20 capable of grasping and separating the bows of the top, is open on the side toward the vehicle so that the continuous curtain above referred to is provided for when the top is collapsed without injury thereto; this, in 25 combination with means for moving the holding parts of the bow holder out of the path of travel of the bows, as they move between open and closed position, and vice versa.
- 30 The invention further consists in the features and details of construction hereafter more fully set forth in the specification and claims.

Referring to the drawings, in which similar numerals indicate the same parts throughout the several views,

Figure 1 is a perspective view of a vehicle and top showing the device of this invention applied thereto in position ready to have the bows of the top lowered into it prior to securing them in place.

Fig. 2 shows the top collapsed and the device of this invention applied to the bow.

Fig. 3 is a side view of the device of this invention in the same position as in Fig. 2,

the bows and solid curtain being shown in cross-section.

Fig. 4 is a perspective view of the device of Fig. 3, the bows and curtain being removed therefrom.

Fig. 5 is a bottom view of the device illustrated in Fig. 3.

Fig. 6 is a perspective changed position view of the parts appearing at the top of Fig. 4.

The top to be taken care of by this device of this invention is illustrated in the drawings as having side bows 10, 11, 12 and 13, and differs from tops ordinarily taken care of by devices of the type of my prior 65 patent in that the back of the vehicle is closed by a solid curtain 14 which is, as shown in Figs. 1 and 3, attached at its sides to the bottom bow 10, as well as to the vehicle body 16 in the line 18, it being 70 obviously attached to the upper portion or top proper in the line 20, and the problem solved by this invention is to provide means for readily securing all of these bows 10—13 together while accommodating this curtain 75 14, permanently attached to the bottom bow 10.

The bow holder for accomplishing the desired result comprises a relatively short fixed stock 22 secured to the vehicle body 16 80 by any well known securing device, forming no part of this invention, such for instance as the bracket base 24 and arm 26.

Hinged to the stock 22 on the bearing pin 30 by any convenient type of hinge is the 85 movable arm 32 made appreciably longer than the stock 22, and of sufficient length so that its upper curved end 34 embraces the upper edge of the upper bow 13 when the bows of the vehicle are in folded position, 90 as shown. Suitably secured upon the stock 22, preferably upon a bracket 36 extending therefrom, is a spring 38, held in tension by the clip 40, and provided with a notch or recess 42 into which the lug 44 on the 95 bottom of arm 32 normally drops, as shown, with the result that the arm 32 is locked in the position shown in Fig. 3 by this spring 38. In the particular case here illustrated, the spring 38 is made of a loop of wire as 100

shown particularly in Fig. 4, and there is a lug 44 on each side of the device, as shown in dotted lines in that figure, but this duplication of parts is not essential to the spirit of this invention. When the spring 38 is moved from the full line to the dotted line position of Fig. 3, these lugs 44 bear against a solid portion 46 of the stock 22 provided for the purpose and prevent the arm 32 moving in a counter-clockwise direction farther than the dotted line position shown, in which position the arm 32 is out of the way of the bows 10—13.

At the upper end of the arm 32 on ears 48 provided for the purpose there is pivoted at 50 a locking lever 52 having a handle 54 for handling by the operator. Pivoted on this lever at 55 between the pivot 50 and the handle 54 is a spring material jaw 56 made, as clearly shown in the drawings, with angular portions 58 adapted to bear in the notches 60 on the opposite sides of an intermediate projecting tongue 62 on the extreme end of portion 34, heretofore referred to, of arm 32. This spring member 56 terminates in the downwardly extending portion 56^a adapted to inclose and grasp the upper bow 13 when all the parts are in the operative position shown in Figs. 2 and 3. The member 56 is so proportioned, and of such a spring material that when the arm 52 is in the position of Figs. 3 and 4 the portions 58 of the member 56 are held with substantial pressure in the notches 60, but on swinging the lever 52 to the position shown in Fig. 6, the member 56 can be moved in a counter-clockwise direction about the pivotal point 55 from the position of Figs. 3 and 4 to that of Fig. 6 where the bow is released and thence to a position where the member 56 hangs down against lever 52 and is, therefore, entirely out of the way of the bows of the vehicle top to which the device is applied, as they are inserted in and removed from the bow holder. However, in ordinary practice, the arm 32 should, when in the dotted line position of Fig. 3, be far enough from the vertical position so that the bows will clear the device even when the member 56 is locked in the position shown in Fig. 4, in which position the device is carried when the top is up and before the operator has released spring catch 38 for the purpose of moving the arm 32 so that the bows can be admitted within the bow holder.

Having thus described my invention, what I claim as new and desire to secure by Letters Patent, is:

1. In a device of the class described, a fixed stock, an arm longer than the stock hinged at one end thereto, and a gripping jaw pivoted near the other end of the arm adapted to move between two different positions; in one of which it hangs over the end of the arm without reaching as far as

the stock to secure a bow adjacent to said arm by engaging its side opposite to the arm and in the other of which it is back of the arm out of the way and manually operated mechanism for moving the gripping jaw. 70

2. In a device of the class described, a fixed stock, an arm longer than the stock hinged at one end thereto, and a gripping jaw pivoted near the other end of the arm adapted to move between two different positions; in one of which it hangs over the end of the arm without reaching as far as the stock to secure a bow adjacent to said arm and in the other of which it is back of the arm out of the way, an operating lever connected to said gripping jaw and to the arm adapted to effect locking of the gripping arm when in the first mentioned position. 75

3. In a device of the class described the combination of a fixed support, an arm pivoted near its bottom to said fixed support, adapted to swing upward against one side of a bow to be held in position, a lever pivoted adjacent to the upper end of the arm, a hook member pivoted to and wholly supported by the lever adapted to detachably lock over and extend beyond the upper end of said arm to hold said bow adjacent to said arm, the points of connection of the lever to the arm and the hook to the arm being such that locking of the hook to the arm is effected when the lever is in substantial contact with the arm. 90

4. In a device of the class described, the combination with a fixed support, an arm pivoted near its bottom to said fixed support, adapted to swing upward against one side of a bow to be held in position, there being a rigid extension of said arm extending over the top of such a bow, a lever pivoted to said extension, and a spring locking hook member pivoted at one end to said lever intermediate between the lever ends, the opposite end of the hook member being free to swing around said pivot, said hook member having a portion hooking over and normally bearing on the upper end of said arm and having a portion extending from the end of said arm parallel to the arm to embrace a bow placed adjacent to the arm. 110

5. In a device of the class described, the combination of a fixed support, an arm pivoted near its bottom to said fixed support, adapted to swing upward against one side of a bow to be held in position, there being a rigid extension of said arm extending over the top of such a bow, a lever pivoted to said arm, and a spring locking hook member pivoted at one end of said lever intermediate between the lever ends, the opposite end of the hook member being free to swing around said pivot, said hook member having a portion normally bearing on the end of said arm and having a portion extending from the end of said extension downward 130

parallel to the arm, the point of pivot of the locking member to the arm and the point where the locking member bears against the end of the arm being slightly out of line with the pivotal point of the lever, whereby locking is effected through the fact that the end of the lever in this position bears solidly against the arm.

In witness whereof, I have hereunto subscribed my name in the presence of two witnesses.

CLARENCE L. BAIR.
